C. S. BUSHNELL

AUTOMATIC TRAIN CONTROL SYSTEM

Original Filed Dec. 16. 1916

UNITED STATES PATENT OFFICE.

CHARLES S. BUSHNELL, OF SYDNEY, NEW SOUTH WALES, AUSTRALIA, ASSIGNOR TO
GENERAL RAILWAY SIGNAL COMPANY, OF GATES, NEW YORK, A CORPORATION OF
NEW YORK.

AUTOMATIC TRAIN-CONTROL SYSTEM.

Application filed December 16, 1916, Serial No. 137,409. Renewed March 8, 1923.

To all whom it may concern:

Be it known that I, CHARLES S. BUSHNELL, a citizen of the United States, and a resident of the city of Sydney, State of New South Wales, Commonwealth of Australia, have invented a new and useful Automatic Train-Control System, of which the following is a specification.

This invention relates to automatic train control systems, more particularly to the impulse devices and trackway circuits necessary for the proper control of the train.

In one type of automatic train control system, to which this invention more particularly relates, the apparatus on the train which controls the movement thereof is set into operation when it is desired to control the train and continues in operation until the desired control has been accomplished, whereupon this apparatus is reset or restored to its initial or normal condition ready for the next operation. In other words, train control systems of this type may be said to have a cycle of operation, which is initiated at the point at which it is desired to commence a reduction in speed and which is terminated by the restoration of the train control apparatus to the initial condition at the point where further reduction in speed is not desired. In general the initiating point is the entrance to a block when the next block in advance is occupied, and the terminating point at the end of that block when the next block in advance is not occupied. It may well happen, however, that after the initiation of the cycle at the entrance to a block by reason of the fact that the next block in advance is occupied and before the train has traveled through the length of the first block, the train formerly in the block in advance has left that block so that it is proper to restore the apparatus on the first train to its initial condition.

With these considerations in view the primary object of this invention is an arrangement and construction of parts in an automatic train control system such that the cycle of operation of the apparatus on a train following its initiation at the entrance to a block may be terminated at intermediate points in the block.

Other objects and advantages will appear as the description of the invention progresses, and the novel features of the inven-

tion will be particularly pointed out in the appended claims.

In describing the invention in detail, reference is had to the accompanying drawing, wherein I have illustrated a preferred physical embodiment of my invention, and wherein like characters of reference designate corresponding parts throughout the several views, and in which:

Fig. 1 is a diagrammatic view showing a simplified construction of a train control apparatus to which this invention is applicable, together with the construction and arrangement of parts embodying this invention; and Fig. 2 is a diagrammatic view of a portion of a railroad track and illustrates an arrangement of trackway circuits suitable for controlling the train control apparatus shown in Fig. 1.

Referring to the accompanying drawing, numeral 1 designates a portion of a track rail of the ordinary railroad track upon which the wheels of the vehicle or train travel; and for simplicity the vehicle or train is shown as comprising one wheel 2 and an axle 3. According to the embodiment of the invention illustrated communication between the track and the vehicle used for the proper control of the train control apparatus on the vehicle is obtained by the mechanical and electrical cooperation of a contact shoe carried by the vehicle with suitable ramps or contact rails located along the track. These contact shoes may be of any suitable construction, and for simplicity are shown diagrammatically in the accompanying drawing as comprising a vertically movable plunger 5 slidably mounted in a bracket 4 carried by the vehicle in any suitable manner and for simplicity assumed to be made of wood or other suitable insulating material. The shoe or plunger 5 is provided with a suitable foot or enlargement at its lower end constituting the portion thereof which engages the ramps; and said plunger is pressed downward to its lower position, shown in Fig. 1, by means of a compression spring 7 interposed between the bracket 4 and a collar 6 fixed to said plunger. Secured to the upper end of the plunger 5 is a button 8 of suitable insulating material which is larger than the stem portion of said plunger and which is adapted to form a stop for limiting the

downward movement thereof; and this button 8 is arranged to lift a contact spring 9 secured to the bracket 4 out of electrical contact with a contact piece 10 on said bracket when the plunger 5 is raised.

In the simplified construction of the train control apparatus illustrated, a worm 11 is fixed to the axle 3 and meshing with said worm is a worm gear 12 secured to the lower end of a shaft 13 which is revolubly mounted in suitable supports 14 and is held against endwise movement in said supports by suitable collars 15 pinned to said shaft. Secured to the shaft 13, as by means of a pin 16, is a collar or block 17; and slidably mounted on the shaft below the block 17 is another block 18. Pivotaly connected to the block 17 are links 19 which are also pivotaly connected to weighted balls 20; and similarly connecting the balls 20 with the block 18 are other links 19. A compression spring 21 is interposed between the two blocks 17 and 18. The construction described will be readily recognized as that of a conventional speed responsive device similar to that of the well known centrifugal governor, and the operation of this speed responsive device will be apparent without further explanation. Journalized on a fixed stud 22 is an angle lever L, one arm 23 of which extends to the speed responsive device above described and is formed with bifurcations 24 carrying rollers 25 engaging with flanges 26 secured to the block 18, so that as the block 18 moves up and down in response to changes in the speed of rotation of the shaft 13, the arm 23 of the angle lever L is correspondingly moved up and down.

In the embodiment of the invention illustrated the device for establishing or determining the desired permissive speeds for the vehicle at different points in its travel is shown as a cam which is adapted to be connected to the wheels of the vehicle when desired so that it may be gradually turned as the vehicle travels. In the simplified construction illustrated a beveled gear 27 is fixed to the shaft 13 and meshes with a similar beveled gear 28 secured to a shaft 29 which is journalized in supports 30 and is held against endwise movement in said supports by suitable collars 31 fastened to said shaft. Fixed to the shaft 29 is a worm 32 which meshes with a worm gear 33 mounted on a fixed bearing stud or pin 34. A smaller gear 35 is connected to the gear 33 so as to turn therewith, and this smaller gear meshes with a larger gear 36 journalized on a bearing stud 37. In a similar way intermeshing gears 38, 39, 40 and 41 are journalized on bearing studs 43 and 44, and serve to complete a train of gears which will be recognized as the well known reduction gearing. Pivotaly mounted at one end on the bearing stud 44 is a lever

45 which carries two intermeshing gears 46 and 47, the gear 46 being also in mesh with a gear 42 connected to the gear 41.

Disposed above the outer or free end of the lever 45 is an electromagnet, herein termed the cam control magnet K, which comprises two coils 48, the pole pieces of which are connected at their lower ends by the usual yoke 49, said yoke being fastened to suitable fixed lugs or supports. The armature 50 of the cam control magnet K is guided by pins 51 secured in the pole pieces of the coils 48, and this armature 50 is rigidly connected to a rod 52 which extends downward through a guiding opening in the yoke 49 and which is pivotally connected to the outer end of the lever 45. A collar 53 is fixed to the rod 52, as by means of a pin, and interposed between said collar and the yoke 49 is a compression coil spring 54 which tends to move the rod and lever 45 to their upper position.

Disposed above the lever 45 and the gears 47 and 46 carried thereby is a cam shaft 55 supported in suitable bearings (not shown), and fixed to this cam shaft 55 is a gear 56 which is arranged in the same plane as the gear 47, so that when the lever 45 is in its upper position, opposite to the position shown in Fig. 1, the gear 47 may mesh with the gear 56. Suitable means is provided for returning the cam shaft 55 to its initial position, and in the simplified construction illustrated this result is accomplished by a counterweight 57 fastened to the gear 56, so that when the cam shaft 55 is free to turn it is moved to the position shown in Fig. 1 by the counterweight 57 which tends to assume a position directly underneath the shaft 55. Fixed to the cam shaft 55 is a cam-shaped plate, herein termed the cam 58. The factors determining the shape of this cam 58 will be explained hereinafter. Also rigidly secured to the cam shaft 55 is another plate 59 the periphery of which is formed with two concentric portions, of different radius, whereby shoulders 60 are formed in the periphery of said plate for the purpose more fully explained hereinafter.

The arm 61 of the angle lever L extends to a point below the cam shaft 55 and is pivotally connected to the lower end of a floating lever 62 which carries at its upper end a roller 63 bearing against the edge of the cam 58. A link 64 is pivotally connected at one end to the middle point of the floating lever 62 and at its other end to an arm 65 secured to a contact sector 66 which is revolubly mounted on a fixed pin or stud 67. The outer edge of the contact sector 66 is formed with a shoulder 68 for the purpose hereinafter explained. Arranged adjacent to the contact sector 66 is a suitable fixed support 69 which carries contact supporting

blocks 70 of insulating material; and anchored at one end to the support 69 is a tension spring 71, which is connected at its other end to the arm 65. Fastened to the 5 contact supporting blocks 70 and the support 69 are a number of contact supports 72 which support contact fingers 73, 74, 75 and 10 76 and which also serve as binding posts for establishing electrical connection to said 10 contact fingers.

Each of these contact fingers is mounted 15 on its corresponding support 72 in the same manner and a description of one will suffice for all. Referring to the contact finger 76, this finger is formed at its lower end with a pair of ears 77 which are connected by a horizontal pin 78 to the corresponding contact support 72, this construction serving to support the contact finger 76 so that it 20 may be rocked in a vertical plane. The contact finger 76 is pressed in one direction, toward the left as viewed in Fig. 1, by a compression spring 79 mounted upon a pin secured to the contact support 72 in any 25 suitable manner.

Secured to the lefthand face of the contact finger 73 is a freely revoluble roller 80 of insulating material which is arranged to bear against the edge of the contact sector 30 66. Normally, when the parts are in the position shown in Fig. 1, the contact finger 73 is moved some distance to the right from its contact support 72, and the cooperating contact finger 74 is also moved a distance 35 from its contact support, the distance between the contact finger 74 and its support, however, being less than the distance between the contact finger 73 and its support; and it is apparent that if the contact finger 40 73 were allowed to move to the left, the contact fingers 73 and 74 would separate since the contact finger 74 would move only a short distance compared with the distance which the contact finger 73 would move. 45 The contact fingers 75 and 76 are also normally closed and will separate when the contact finger 75 is permitted to move toward the left, as viewed in Fig. 1.

A rock lever 82 is pivotally mounted on 50 a fixed pin 81 and is arranged in the same plane as the plate 59, and carried by said rock lever is a freely revoluble roller 83 which is pressed against the edge of said plate by a tension spring 84. To the upper 55 end of the rock lever 82 is connected a link 85 which is adjustably connected, as by means of nuts 87, to another link 86 which is pivotally connected to the upper end of the contact finger 75.

According to the embodiment of the invention illustrated, it is contemplated that the speed of the vehicle will be retarded by the well known system of air brakes; but 60 since this system of brakes is well known to those skilled in the art, no attempt has been 65 made to show the construction and arrangement of its parts in detail. As is well known, this system of air brakes includes a train pipe 88 and the venting of this train pipe causes an application of the brakes. In 70 order that the train control apparatus may automatically cause such an application of the brakes a suitable valve 89 is connected to the train pipe 88 and is arranged to be operated by a solenoid 90, the arrangement 75 preferably employed and illustrated in Fig. 1 being that in which the valve 89 is closed when the solenoid 90 is energized and is automatically opened by a spring or other means when said solenoid is deenergized. 80

The speed control apparatus is governed electrically by a relay SC on the vehicle and hereinafter termed the speed control relay; and this speed control relay SC is provided with two armatures or contact fingers 85 91 and 92, which are illustrated conventionally. The speed control relay SC is in turn controlled by another relay P carried on the vehicle, and hereinafter termed the pick-up relay; and this pick-up relay P is provided 90 with one armature or contact finger 93.

In Fig. 2 there is shown a stretch of track, over which traffic normally moves from left to right, in the direction indicated by the arrow T; and the track rail 1¹ of this stretch 95 of track is divided by insulating joints 94 in the usual manner into blocks, as the blocks A, B, and C, the entire length of only the the block B being shown. In the particular embodiment of the invention illustrated, the 100 trackway circuits are supplied with alternating current derived from a suitable source as a generator 95, which is connected to line wires 96 and 97 extending throughout the length of the railroad. The parts and electrical conductors associated with each block 105 are substantially the same, and these parts and conductors are for convenience given corresponding reference characters with distinguishing exponents added thereto. Ad- 110 jacent to one end of each block, preferably the exit end thereof, is located a track transformer 98, the primary of which is connect- 115 ed across the line wires 96 and 97, and the secondary of which is connected across the track rails 1 and 1¹ of the corresponding block. At the other end of each block a 120 track relay 99 is connected across the track rails, this relay being of suitable construction so as to be responsive to alternating current and being provided with two contact fingers or armatures 100 and 101. The secondary of the track transformer 98 of each block, the track rails of that block, and the track relay 99 connected thereto constitute 125 the well known normally closed track circuit, the operation of which will be understood by those skilled in the art of railway signaling without further explanation. As- 130 sociated with each block and preferably lo-

cated adjacent to the entrance end thereof is a contact rail or ramp R which is of suitable construction and is supported in any suitable manner on the ties supporting the track rails, but so as to be insulated from said track rails. The different ramps R are disposed in such a position with reference to the track rails that they will be engaged by the contact shoe 5 on a passing vehicle. Between the ends of some or all of the blocks are located other ramps RI of similar construction, herein termed intermediate releasing ramps, there being any number of these intermediate releasing ramps at any desired distances apart located along the first and greater part of each block for the purpose hereinafter more fully explained. Associated with each ramp R is a transformer 102, the primary of which is connected across the line wires 96 and 97.

The conductors and electrical connection between the different parts of the train control system shown in Fig. 1 and Fig. 2 will not be described in detail, since the various operating circuits of the system will be fully traced and explained in the description of the operation.

Referring to Fig. 1, the shape of the cam 58 is determined from the braking curve of the vehicle carrying that cam for a stretch of track of certain particular physical characteristics. In general it may be said that the shape of the cam 58 is selected so that when said cam is gradually turned by the progress of the vehicle it causes the roller 63 to assume different positions in accordance with a predetermined decrease in the permissive speed for the vehicle, in order that the position of the roller 63 at any point in the travel of the train following the initial operation of the cam 58 may correspond to the permissive speed at that point which the vehicle should not exceed if it is to be brought to a stop or to a predetermined low speed by an application of its brakes before reaching a certain point in advance, generally the entrance end of the next block. In the particular kind of cam illustrated, the lengths of the radii of said cam correspond to speed and the angular displacement of said cam from its initial position, shown in Fig. 1, corresponds to distance traveled by the vehicle after the cam commences to move. The manner in which the cam 58 cooperates with the speed indicator or speed responsive device so as to cause an automatic control of the vehicle whenever its speed exceeds the desired permissive speed will be more fully explained hereinafter in the description of the operation. In this connection it should be understood that while the shape of the cam 58 shown in Fig. 1 illustrates in a general way the shape of a cam which may be used in practice, no attempt has been made to show this cam precisely

correct in shape. Furthermore, as indicated hereinbefore, the shape of the cam 58 is determined with reference to a certain stretch of track, having certain grades, curves, or other factors characteristic of this stretch of track which affects the retarding effect of the brakes on a vehicle; and, as is well known by those skilled in the art, in practice the different stretches of track or blocks of a railroad will not be necessarily of the same length, nor of the same grade, nor will the other physical characteristics, such as curves be the same, so that if it is desired to control the speed of a vehicle in these several blocks having different physical characteristics precisely in accordance with the braking curves of the vehicle for these several blocks, it is apparent that some provision other than a single cam 58 must be made. Such provisions form no part of this invention, however, and do not modify the principles or operation of the system embodying this invention, and it has been deemed sufficient to illustrate only one cam.

Operation.—The parts of the speed control apparatus are shown in Fig. 1 in the position which they assume when there is no other vehicle or train ahead requiring the following vehicle to proceed cautiously and reduce its speed. When the parts are in this position, which may be termed the normal or initial position, the speed control relay SC is energized by a circuit which may be traced as follows: commencing at the battery 103, conductor 104, relay SC, conductors 105 and 106, armature 91 in its upper position, conductor 107, contact spring 9, contact piece 10, and conductors 108 and 109 back to the battery 103. The speed control relay SC may also be energized by another circuit controlled by the pick-up relay P, said another circuit being traced as follows: commencing at the battery 103, conductor 104, relay SC, conductors 105 and 110, armature 93 of the relay P in its upper position, and conductors 111 and 109 back to the battery 103. One terminal of the winding of the relay P is connected by conductor 112 to the frame or axle of the vehicle, so that this conductor is electrically connected to the track rails, and the other terminal of the winding of the relay P is connected by a conductor 113, preventive resistance 114, and conductor 115 to the contact shoe 5. There is a low resistance shunt for the preventive resistance 114 comprising conductors 116 and 117 which is closed by the contact fingers 75 and 76 when the parts of the train control apparatus are in the normal condition as shown in Fig. 1.

When the speed control relay SC is energized and its armature 92 is in its upper position, the cam control magnet K is energized by a circuit which may be traced as follows: commencing at the battery 118, con-

ductor 119, armature 92 in its upper position conductor 120, cam control magnet K and conductor 121 back to the battery 118.

The brake controlling solenoid 90 is also normally energized by a circuit which may be traced as follows: commencing at the battery 122, conductor 123, contact fingers 73 and 74, conductor 124, solenoid 90, and conductor 125 back to the battery 122.

Assume that a vehicle, equipped with the train control apparatus as shown in Fig. 1 and having that apparatus in its normal or initial condition, is in the block A and about to enter the block B; and further assume that neither the block B nor the block C is occupied by another train. Since the block B is not occupied, the track relay 99 is energized so that a partial circuit establishing a difference of potential equivalent to the voltage of the entire secondary of the transformer 102 is established between the ramp R and a track rail, said partial circuit being traced as follows: commencing at the ramp R, conductor 126, armature 100 in its upper position, conductor 127, secondary of the transformer 102, and conductor 128 to the track rail 1. When the vehicle in question proceeds to the point where its contact shoe 5 engages the ramp R, said contact shoe is lifted by the mechanical co-operation of said shoe and said ramp and is also electrically connected to said ramp. The lifting of the contact shoe 5 interrupts the normally closed circuit hereinbefore traced for energizing the speed control relay SC; but under the traffic conditions assumed the pick-up relay P is energized by a circuit which may be traced as follows: commencing at the ramp R, conductor 126, armature 100 in its upper position, conductor 127, secondary of the transformer 102, conductor 128 to the track rail 1, through the wheels and axles of the vehicle, along conductor 112 to the relay P, thence along conductors 113 and 117, contact fingers 76 and 75, conductors 116 and 115 to the contact shoe 5 and back to the ramp R. The pick-up relay P being energized maintains the speed control relay SC energized by closing the circuit therefor controlled by its armature 93. As the vehicle in question progresses and the first pair of wheels and axle thereof enter the block B the track relay 99 is shunted and its armature 100 drops thereby interrupting the partial circuit associated with the ramp R, but since the block C is not occupied there is established another partial circuit which supplies current to the pick-up relay P and maintains it energized, this last mentioned partial circuit being traced as follows: commencing at the ramp R, conductor 126, armature 100 in its lower position, conductors 129 and 130, armature 101¹ in its upper position, conductor 131 to an intermediate tap 132 of the secondary of the transformer 102¹,

and conductor 128¹ to the track rail 1. It can be seen that the difference of potential established between the ramp R and the track rail 1 by the last traced partial circuit less than that established by the first traced 70 partial circuit associated with said ramp. The pick-up relay P is so constructed that when the preventive resistance 114 is included in its circuit the higher difference of potential above mentioned will cause sufficient current to flow through said relay to raise its armature 93, but the low difference of potential will not cause sufficient current to flow through said relay to raise its armature. When the preventive resistance 114 is 80 shunted, however, the low difference of potential is sufficient to cause the relay P to raise its armature 93. Under the particular conditions assumed the preventive resistance 114 is shunted so that the low difference of 85 potential established between the ramp R and the track rail 1 after the first pair of wheels and axle of the vehicle under consideration have entered the block B is sufficient to maintain said relay P energized, and in turn keep the speed control relay SC energized. Consequently under the traffic conditions assumed, that is, when neither the block B nor the block C is occupied, the vehicle may enter the block B without having 95 the normal condition of its speed control apparatus changed.

For the next condition of traffic to be considered assume that the vehicle in question is in the block A and about to enter the block B, and that while the block B is not occupied by another train, another train does occupy the block C. The same operation of parts occurs before the first pair of wheels and axle of the vehicle in question enter the 105 block B as has been previously described; but after the vehicle has entered the block B and the armature 100 of the track relay 99 has dropped, there does not exist any difference of potential between the ramp R and the track rail 1 by reason of the fact that a train is assumed to occupy the block C so that the armature 101¹ of the track relay 99¹ is in its lower position. Consequently, the armature 93 of the pick-up relay P drops 110 because current is no longer supplied to said pick-up relay P, and since the contact shoe 5 is still in engagement with the ramp R, all supply of current to the speed control relay SC is cut off, and hence 115 the armature of said relay SC drops. The dropping of the armature 91 of the speed control relay SC opens another break in the normally closed circuit for energizing said relay, so that after the contact shoe 5 has left engagement with the ramp R and the contact spring 9 has again made electrical contact with the contact piece 10, nevertheless the normally closed circuit for energizing said relay SC remains 120 125 130.

broken. The dropping of the armature 92 of the speed control relay SC interrupts the normally closed circuit hereinbefore traced for energizing the cam control magnet K and consequently the spring 54 moves the lever 45 to its upper position so as to bring the gear 47 into mesh with the gear 56, thereby connecting the cam shaft 55 with the wheels of the vehicle. The cam-shaft 55 and the cam 58 carried thereby are now turned gradually in accordance with the distance traveled by the vehicle, so that the upper end of the floating lever 62 assumes different positions more and more to the left of that shown in Fig. 1 as the permissive speed of the vehicle desired decreases. The lower end of the floating lever 62 is connected to the arm 61 of the angle lever L and is caused to assume different positions more and more to the left of that shown in Fig. 1 according to the actual speed of the vehicle as measured by the speed responsive device. If it happens, and this is usually the case under ordinary circumstances, that the vehicle as it passes the ramp R is traveling at a comparatively high rate of speed, the lower end of the floating lever 62 will be in a position to the left of the position shown in Fig. 1 such that the contact sector 66 will be rocked downward until the shoulder 68 is only a short distance above the roller 80. As the vehicle progresses and the cam 58 causes a movement of the upper end of the floating lever 62 more and more to the left, it can be seen that the lower end of said floating lever must be moved a corresponding extent to the right in order to prevent further movement of the link 64 to the left, as it is viewed in Fig. 1, and a consequent further movement of the contact sector 66 until the shoulder 68 is brought opposite to the roller 80. If the contact sector 66 is moved far enough to bring the roller 80 opposite the shoulder 68, the contact fingers 73 and 74 are allowed to separate and cause an automatic application of the brakes. In other words, the actual speed of the vehicle which causes the lower end of the floating lever 62 to assume different positions must decrease at the same rate and in the same manner as the permissive speed for the vehicle, determined by the position given to the upper end of the floating lever 62 by the cam 58, decreases, in order that an automatic application of the brakes will not result. From this it can be seen that as the vehicle progresses through the block B it is compelled to reduce its speed in accordance with the desired curve of permissive speed, so that if the movement of the cam 58 continues, the vehicle would be brought to a stop or to a predetermined low speed by the time it reached the end of the block B.

As the vehicle progresses through the block B and the cam shaft 55 is gradually turned in accordance with the distance traveled, the plate 59 is also gradually turned, and after the train has progressed for a certain distance, as for example, for 75 or 80 per cent of the length of the block B, said plate 59 has been turned far enough so that the shoulder 60 comes opposite the roller 83, thereby permitting the spring 84 to move the rock lever 82 to the left and move the contact finger 75 out of contact with the contact finger 76. In other words, the plate 59 and its associated parts, which may be termed a run-down or distance measuring device, measures off the distance traveled by the vehicle into a block and conditions the control of the cam 58 accordingly. In this way, after the vehicle has traveled a predetermined part of the length of the block B into that block, the shunt around the preventive resistance 114 is broken, so that at any point in the remaining part of the block B only a ramp, between which and a track rail a high difference of potential exists, is capable of energizing the pick-up relay P.

Suppose that during the time the vehicle is reducing its speed and traveling through the block B, the train assumed to be in the block C remains in that block; then, when the vehicle in question reaches the ramp R¹ at the entrance to the block C, either a low difference of potential or no difference of potential will exist between this ramp and the track rail 1, by reason of the fact that the armature 100¹ of the track relay 99¹ is in its lower position and is connected to the conductor 129¹ leading to the track relay of the block (not shown) next in advance of the block C, so that if this block next in advance is not occupied a low difference of potential is established, while if this next block in advance is occupied no difference of potential is established. In either case the pick-up relay P is not energized, since the preventive resistance 114 is in series therewith. Suppose, however, that by the time the vehicle in question reaches the end of the block B, the train formerly occupying the block C has moved out of that block. Then, under these conditions, a high difference of potential exists between the ramp R¹ and the track rail 1 so that, regardless of the fact that the preventive resistance 114 is included in series with the pick-up relay P, this pick-up relay P is energized, the speed control relay SC in turn is energized, and finally the cam control magnet K. The energization of the cam control magnet K moves the lever 45 to its lower position and disengages the gear 47 from the gear 56, whereupon the cam shaft 55 and its associated parts are returned to their normal position shown in Fig. 1 by the action of the counterweight 57. In this way, the cycle of operation of the train control apparatus is terminated and the parts are restored to their initial condition ready

for the next operation. The next operation may be caused to occur when the vehicle enters the block C, providing the next block in advance of the block C is occupied, in the 5 same manner and for the same reason as hereinbefore explained in connection with the entrance of the vehicle into the block B when another train occupies the block C.

In order to avoid delaying a following vehicle or train, it should be possible for the train control apparatus on said following vehicle to be released or restored to its initial condition after its operation has once been initiated, as soon as the train which 10 occupied the next block in advance and which was the cause of the initiation of the operation of the train control apparatus, has moved out of that next block in advance. That is, suppose that while the vehicle after 15 having entered the block B and having its train control apparatus set into operation has only proceeded part way through the block B when the train in the block C moves out of that block, it can be seen that it is unnecessary under these conditions to compel 20 a further reduction in speed of the vehicle in the block B; and the most important feature of the system embodying this invention resides in the means for accomplishing the 25 release and restoration of the parts of the train control apparatus on the following vehicle to its initial condition at an intermediate point in a block.

As pointed out hereinbefore, the preventive resistance 114 is shunted during the movement of the vehicle through the first and greater part of the block B, and it can be seen that at any point in this first part of the block a medium difference of potential 30 between a ramp and a track rail is sufficient to energize the pick-up relay P and cause a restoration of the parts of the train control apparatus to the initial or normal condition. Consequently, in order to obtain a 35 release at an intermediate point in a block, as the block B, it is only necessary to place at the different points desired an intermediate releasing ramp, such as the ramp RI, which is connected by a conductor 132 to 40 the conductor 130. When the vehicle first enters the block B, there being another train in the block C, the intermediate releasing ramps RI do not have any difference of potential established between them and a 45 track rail by reason of the fact that the armature 101¹ of the track relay 99¹ is in its lower position; but it can be seen that as soon as the train leaves the block C and the armature 101¹ returns to its upper position, 50 a medium difference of potential is established between each and all of one or more intermediate releasing ramps RI in the block B, so that as soon as the vehicle in the 55 block B passes one of these intermediate releasing ramps RI the train control appa-

ratus is restored to its normal condition, permitting the vehicle to proceed to the end of the block B without unnecessary delay. If a vehicle should enter the block B when that block is occupied by another train, the intermediate releasing ramps RI would not cause a restoration of the parts of the train control apparatus on that vehicle to the initial or normal condition, even if the block C were not occupied at the time and a low 70 difference of potential existed between said intermediate releasing ramps and a track rail, because when the first vehicle entered the block B, the preventive resistance would be included in the circuit for the pick-up 75 relay P, thereby making the low difference of potential insufficient to raise the armature 93 of said relay P. The preventive resistance 114 would not be shunted under the 80 conditions just assumed when the vehicle entered the block B because the cam shaft 55 would have been turned through an angle equivalent to the length of the block A while the vehicle in question was passing through the block A. 85

Although I have particularly described the construction of one physical embodiment of my invention, and explained the operation and principle thereof; nevertheless, I desire to have it understood that the form 90 selected is merely illustrative, but does not exhaust the possible physical embodiments of the idea of means underlying my invention.

What I claim as new and desire to secure 100 by Letters Patent of the United States, is:

1. In an automatic train control system, in combination: a vehicle and a track therefor divided into track circuit blocks; train control apparatus carried by the vehicle and operating to cause a continuing reduction in speed of the vehicle following its initial operation; a ramp at the entrance to each block; a partial circuit associated with each ramp and controlled by the track circuit of the corresponding block for establishing a difference of potential of a predetermined value between said ramp and said track rail when that corresponding block is not occupied; a second partial circuit associated with each of said ramps and controlled by the track circuit of the next block in advance of the corresponding block for establishing a difference of potential of a predetermined value less than the value established by said first mentioned partial circuit when said next block in advance is not occupied; a relay on the vehicle for governing said train control apparatus; a partial circuit on the vehicle including said relay; means for connecting said partial circuit on the vehicle with the partial circuit associated with each ramp as the vehicle passes the successive ramps; means on the vehicle for preventing said relay from responding to the difference 110 115 120 125 130

of potential established by said second mentioned partial circuit, said means being normally ineffective and being rendered effective after the vehicle has traveled a predetermined part of the length of the corresponding block; and other ramps located between the ends of each block and connected to said second mentioned partial circuit corresponding to that block.

16 2. In an automatic train control system, in combination: a vehicle; train control apparatus carried by the vehicle; a relay for controlling said apparatus; a controlling circuit for said relay; a preventive resistance inserted in said circuit; a normally closed shunt for said resistance; and means governed by the distance traveled by the vehicle for interrupting said shunt.

20 3. In an automatic train control system, in combination: a vehicle; automatic train control apparatus carried by the vehicle; an electrically operable device for governing said apparatus; and means controlled by the distance traveled by the vehicle for changing the operating characteristics of said device.

25 4. In an automatic train control system, in combination: a vehicle and a track therefor; train control apparatus for the vehicle having a cycle of operation corresponding to a predetermined distance traveled by the vehicle; means normally responsive to an impulse of a predetermined character for controlling said train control apparatus to restore it to its initial condition and to hold it in that condition; means for modifying said means to prevent its response to the impulse of said character after the vehicle has traveled a part of said predetermined distance; and traffic controlled impulse devices along the track for governing said first mentioned means.

30 5. In an automatic train control system, in combination: a vehicle and a track therefor divided into blocks; automatic train control apparatus on the vehicle having an initial condition and an ultimate condition and changing gradually from its initial condition to its ultimate condition during the movement of the vehicle over the length of a block; traffic controlled means associated with each block for governing said apparatus to initiate the operation thereof; and other traffic controlled means associated with each block for governing said apparatus and effective to restore it to its initial condition prior to its reaching its ultimate condition but not thereafter.

35 6. In an automatic train control system, in combination: a vehicle and a track therefor divided into blocks; automatic train control apparatus on the vehicle; and impulse devices located at the entrance to each block and at intervals in the first part of that block for controlling said apparatus,

said impulse devices located at intervals in the first part of a block being controlled by the next block in advance and being capable of controlling said apparatus to restore it to its normal position providing 70 said next block in advance is not occupied and provided said block was not occupied when the vehicle entered it.

7. In an automatic train control system, the combination with a vehicle and a track 75 therefor divided into blocks, of automatic train control apparatus on the vehicle adapted when set into operation to continue in operation until restored, impulse transmitting devices at intervals between 80 the ends of each block and capable of transmitting an impulse of a predetermined character to the passing vehicle when the next block in advance is not occupied, control means on the vehicle normally effective to restore said train control apparatus in response to said impulses, means governed in accordance with the progress of the vehicle for preventing said control means from responding to said impulses after the vehicle 85 has traveled a distance corresponding substantially to the length of the block, and means controlled in accordance with traffic conditions in each block for restoring said train control apparatus at the entrance to 90 that block independently of the action of said last mentioned distance controlled means.

8. In an automatic train control system, the combination with a vehicle and a track 100 therefor divided into blocks, of automatic train control apparatus on the vehicle adapted when set into operation to continue in operation until restored, impulse devices at intervals between the ends of each block and 105 energized when the next block in advance is not occupied, control means on the vehicle normally responsive to the energized condition of said impulse devices and adapted to restore said train control apparatus, 110 and means acting after the vehicle has traveled a predetermined distance following the initiation of the operation of said apparatus for preventing said control means from responding to the energized condition of said impulse devices.

9. In an automatic train control system, the combination with a vehicle and a track therefor divided into blocks, of automatic train control apparatus on the vehicle capable of imposing decreasing restrictions on the speed of the vehicle during its progress through a block, impulse transmitting means at the entrance to each block capable of transmitting to the passing vehicle 125 an impulse of a predetermined character when the corresponding block is not occupied, other impulse transmitting means at intervals between the ends of each block and adapted to transmit an impulse of a 130

- different character when the block next in advance is not occupied, control means on the vehicle for restoring said train control apparatus to a higher speed condition, 5 means governed in accordance with the progress of the vehicle and set into operation and restored in correspondence with said train control apparatus for changing said control means when the vehicle has 10 traveled substantially the length of the block, said control means when unchanged being responsive to the impulses of both characters, but when changed only to the impulse of the predetermined character 15 transmitted by the first mentioned impulse transmitting means, whereby the train control apparatus on a vehicle may be restored to its initial condition at intermediate points in a block when traffic conditions in the 20 block next in advance become safe but cannot be restored at such intermediate points behind another vehicle occupying the same block.
10. In an automatic train control system, 25 the combination with a vehicle and a track therefor divided into blocks, of automatic train control apparatus on the vehicle adapted when set into operation to impose decreasing limitations on the speed of the vehicle during its progress through a block and to continue in action until restored, means associated with each block for setting said apparatus into operation when the vehicle enters a caution block next in the 30 rear of an occupied block, means associated with each block for restoring said apparatus at intermediate points in such caution block when traffic conditions in the next block in advance become safe, and means governed 35 in accordance with the progress of the vehicle for rendering said last mentioned means ineffective after the vehicle has traveled a distance corresponding substantially to the length of the block.
- 40 11. In an automatic train control system, the combination with a vehicle and a track therefor divided into blocks, of automatic train control apparatus on the vehicle adapted when set into operation to limit the speed of the vehicle to a predetermined low speed after the vehicle has traveled through a block and to continue such limitation until restored, a control device for governing said apparatus, trackway impulse devices governed in accordance with traffic conditions for transmitting impulses of distinctive characters to the passing vehicle at different points in a block to influence said control device, and means governed 45 in accordance with the progress of the vehicle for preventing said control device from being influenced by impulses of one character after the vehicle has traveled a predetermined distance.
- 50 12. In an automatic train control system, 55 the combination with a vehicle and a track therefor divided into blocks, of automatic train control apparatus on the vehicle adapted when set into operation to continue in operation until restored, impulse transmitting means at the entrance to each block adapted to cause said apparatus to be restored or set into operation respectively in accordance with traffic conditions in the corresponding block and the next block 60 in advance, other impulse transmitting means at intervals between the ends of each block and capable of transmitting a restoring impulse of a predetermined character to the vehicle when the next block in advance is not occupied, a control device on the vehicle normally responsive to said restoring impulses and effective to restore said apparatus, and means acting after the vehicle has traveled a distance bearing a predetermined relation to the length of the block through which the vehicle is then passing for preventing said control device from responding 65 to said restoring impulses.
- 70 13. In an automatic train control system, the combination with a vehicle and a track therefor divided into blocks, of automatic train control apparatus on the vehicle, a control relay for governing said apparatus, impulse transmitting means at intervals between the ends of each block and normally effective to cause energization of said relay when the next block in advance is not occupied, and means governed in accordance 75 with the progress of the vehicle for preventing such energization of the control relay after the vehicle has traveled a distance corresponding substantially with the length of a block.
- 80 14. In an automatic train control system, in combination, a vehicle and a track therefor divided into blocks, an impulse device at the entrance to each block and adapted to transmit to the passing vehicle an impulse of one kind when the corresponding block is not occupied, other impulse devices at intervals in each block for transmitting another kind of impulse when the next block in advance is not occupied, automatic train control apparatus on the vehicle adapted when 85 set into operation to change from an initial condition to an ultimate condition during the progress of the vehicle through a block, a control device for governing said apparatus, and means governed by said apparatus for rendering said control device responsive to either kind of impulses when said apparatus is in its initial condition but only to the first mentioned kind of impulses after said apparatus has attained its ultimate condition.
- 90 15. In an automatic train control system, the combination with a vehicle and a track therefor divided into blocks, of automatic train control apparatus on the vehicle adapt-

ed when active to impose a continuing restriction on the movement of the vehicle until restored, means partly on the vehicle and partly along the track for restoring said apparatus or rendering it active respectively at the entrance to each block in correspondence with traffic conditions in that block and the next block in advance, means partly on the vehicle and partly along the track normally capable of restoring said apparatus at intermediate points in a block when traffic conditions in the next block in advance become safe, and means rendered active simultaneously with the train control apparatus and governed in accordance with the progress of the vehicle for preventing said last mentioned means from acting after the vehicle has traveled a distance corresponding substantially with the length of the block.

16. In an automatic train control system, the combination with a vehicle and a track therefor divided into blocks, of automatic train control apparatus on the vehicle including a permissive speed device adapted when operating to change to an ultimate condition during the progress of the vehicle through a block, a control device for restoring said permissive speed device to its initial condition, impulse transmitting means between the ends of each block normally effective to influence said control device when the next block in advance becomes unoccupied, and means for preventing the response of said control device to the influence of said impulse transmitting means after the permissive speed device has changed to a predetermined extent.

17. In an automatic train control system, the combination with a vehicle and a track therefor divided into blocks, of automatic train control apparatus on the vehicle including an element adapted to change gradually from an initial condition to an ultimate condition, a control relay on the vehicle for governing said element, a circuit for energizing said relay, means for applying currents of different voltages to said circuit at points along the track, and means governed in accordance with the progress of the vehicle for changing the opposition to the flow of current in said circuit.

18. In an automatic train control system, the combination with a vehicle and a track therefor, of automatic train control apparatus including a permissive speed device adapted to be driven by the wheels of the vehicle, a control relay for governing said permissive speed device, an element also geared to the wheels of the vehicle, a circuit controller operated by said element when the vehicle has traveled a distance corresponding to a change of the permissive speed device to a predetermined extent, and means actuated by said circuit controller

for controlling the energization of said control relay.

19. In an automatic train control system, the combination with a vehicle, of automatic train control apparatus therefor including an element adapted when operating to change gradually in accordance with the distance traveled by the vehicle, means partly on the vehicle and partly along the track for controlling said element in accordance with traffic conditions in advance, and means effective after said element has changed to a predetermined extent for regulating the effective action of said first mentioned means.

20. In an automatic train control system, the combination with a vehicle and a track therefor divided into blocks each provided with a track relay, of an impulse device at the entrance to each block, a circuit for energizing said impulse device including a front contact of the track relay of the corresponding block, a second circuit for energizing said impulse device including a back contact of the track relay of the corresponding block and a front contact of the track relay of the block next in advance, sources of current of different electrical characteristics, included in said circuits, and other impulse devices located at intervals between the ends of each block and energized by said second circuit.

21. In an automatic train control system, in combination, a track divided into blocks, an impulse device at the entrance to each block adapted to transmit impulses of a predetermined character to a passing vehicle when the corresponding block is not occupied, and other impulse devices at intervals along each block and adapted to transmit impulses of a different character to a passing vehicle when the next block in advance is not occupied.

22. In an automatic train control system, the combination with a vehicle and a track therefor divided into blocks, of automatic train control apparatus on the vehicle a normally energized relay on the vehicle governing said apparatus, means for causing energization and deenergization of said relay successively at the entrance to each block in accordance with traffic conditions in the corresponding block and the next block in advance respectively, other means controlled in part by said relay for causing energization of said relay at points between the ends of each block when the next block in advance is not occupied, provided the block through which the vehicle is then passing was not occupied at the time the vehicle entered it.

23. In an automatic train control system, the combination with a vehicle and a track therefor divided into blocks, of automatic train control apparatus for the vehicle

- adapted when operating to impose decreasing limitations upon the speed of the vehicle as it progresses, and means including impulse devices and controlling circuits therefor adapted to set said apparatus into operation upon entrance of the vehicle into a block next in the rear of a block occupied by another vehicle, said means being also adapted to cause restoration of said train control apparatus at intermediate points in the block when the next block in advance becomes clear.
24. In an automatic train control system, the combination with a vehicle, of automatic train control apparatus therefor comprising a permissive speed device adapted to change in accordance with the progress of the vehicle along the track, a relay for controlling said permissive speed device, a circuit for controlling the energization of said relay, and means actuated when said permissive speed device has changed to a predetermined extent for controlling said circuit.
25. In an automatic train control system, the combination with a vehicle and a track therefor divided into blocks, of automatic train control apparatus therefor characterized by changing from an initial to an ultimate condition and by remaining in such ultimate condition until restored, means effective to restore said apparatus at the entrance to each unoccupied block, and other means effective to restore said apparatus at intermediate points in a block provided the apparatus is not then changed substantially to its ultimate condition and the next block in advance is unoccupied.
26. In an automatic train control system, the combination with a vehicle, of automatic train control apparatus therefor including a permissive speed cam adapted to be connected to the wheels of the vehicle, electrically operable means for controlling the driving connection between said cam and the wheels of the vehicle, a circuit controlling the operation of said means, a normally closed circuit controller for governing said circuit, and means moved concurrently with said cam for opening said circuit controller after the cam has moved to a predetermined extent.
27. In an automatic train control system, the combination with a vehicle and a track therefor divided into blocks, of automatic train control means partly on the vehicle and partly along the track adapted to impose restrictions on the movement of the vehicle during its progress through a block next in the rear of an occupied block and to continue such restrictions until restored, governing means normally effective to remove such restrictions by restoring the train control means at intermediate points in a block when the next block in advance becomes unoccupied, said train control means being automatically rendered incapable of responding to said governing means of a block after the vehicle has traveled substantially through the preceding block under its influence, whereby a vehicle can be automatically released from the restrictions imposed upon it by the train control means at intermediate points in a block when traffic conditions in the next block in advance become safe, but cannot be so released at such intermediate points in a block occupied by another vehicle.
28. In an automatic train control system, the combination with a vehicle and a track therefor divided into blocks, of train control means partly on the vehicle and partly along the track and capable of changing to an ultimate condition and imposing gradually decreasing limitations upon the speed of the vehicle during its progress through a block, and means for transmitting to the vehicle a controlling impulse of a distinctive character at the entrance to each block when that block is not occupied, said train control means after changing to a predetermined extent continuing in action until restored by such distinctive impulse.
29. In an automatic train control system, the combination with a vehicle and a track therefor divided into blocks, of automatic train control apparatus for the vehicle including a permissive speed device and an actual speed governor, governing means for said apparatus partly on the vehicle and partly along the track adapted to set said apparatus into operation upon entrance of the vehicle into a block next in the rear of a block occupied by another vehicle and to continue such operation until the next block ahead formerly occupied becomes clear, and means for restoring said apparatus to its initial condition at the entrance to each unoccupied block, said train control apparatus after having been in operation during the travel of a vehicle substantially through a block continuing in action until restored by said last mentioned means at the entrance to an unoccupied block.
30. In an automatic train control system, the combination with a vehicle and a track therefor divided into blocks, of a control relay on the vehicle, a control circuit governing said relay, means for applying current of one character to said control circuit at the entrance to each block when that block is not occupied, other means for applying current of another character to said control circuit at intermediate points in a block when the next block in advance is not occupied, and means governed in accordance with the progress of the vehicle for rendering said relay selectively responsive to both currents in its control circuit or only to the first mentioned current.
31. In an automatic train control system,

- the combination with a vehicle and a track therefor divided into blocks, of train control apparatus for the vehicle adapted to regulate its movement as it travels through a block, 5 said apparatus when operating continuing in operation until restored, and means partly on the vehicle and partly along the track capable of restoring said apparatus at intermediate points in a block when the next 10 block in advance becomes clear, said means being rendered incapable of acting when said apparatus has been changed substantially to its ultimate condition by the travel of the vehicle substantially through a block. 15 32. In an automatic train control system, the combination with a vehicle and a track therefor divided into blocks, of train control apparatus for the vehicle adapted to continue in operation after its initiation until 20 restored, impulse transmitting means for causing restoration of said apparatus, said means being distributed along each block and being effective when the next block in advance is not occupied, and means associated with the train control apparatus for preventing the influencing thereof by said 25 impulse transmitting means of a block when the vehicle enters that block with its train control apparatus acting. 30 33. An automatic train control system for railroads having tracks divided into blocks each provided with a normally closed track circuit, automatic speed control apparatus on a vehicle adapted when set into operation 35 to continue in operation until restored, and means partly on the vehicle and partly along the track for setting said apparatus into operation or restoring it during the progress of the vehicle through a block dependent 40 upon the presence or absence of another vehicle in a block ahead, said means being ineffective as the vehicle passes through a block already occupied, even though the next block in advance thereof is clear. 45 34. An automatic train control system for railroads having tracks divided into blocks each provided with a normally closed track circuit, automatic speed control apparatus on a vehicle and control means therefor 50 having a tendency to assume an active condition, and means partly on the vehicle and partly along the track for communicating a controlling influence to the vehicle during its progress through a block for maintaining said apparatus inactive or restoring it to its inactive condition, said means associated with each block being governed by the track circuit of the block next in advance, said means being ineffective when the vehicle 55 is in a block already occupied by another vehicle ahead. 60 35. An automatic train control system comprising speed control apparatus on a vehicle adapted to enforce predetermined restrictions on the speed of said vehicle, means 65 partly on the vehicle and partly along the track for setting said apparatus into operation in the rear of an occupied block, a run-down device arranged to change gradually to an ultimate condition, a circuit controller 70 opened when said device attains its ultimate condition, and control means for said apparatus governed by said circuit controller. 75 36. An automatic train control system comprising train control apparatus on a vehicle, means partly on the vehicle and partly along the track for controlling the operation of said apparatus in accordance with traffic conditions ahead, and a distance measuring device for governing said apparatus, said 80 device being also controlled by said means. 37. An automatic train control system comprising automatic speed control apparatus on a vehicle, a run-down device governing said apparatus after a predetermined 85 distance of travel of the vehicle while said apparatus is operating, and means partly on the vehicle and partly along the track for controlling the operation and restoration of said run-down device in accordance with 90 traffic conditions. 38. An automatic train control system for railroads divided into blocks, comprising changeable speed controlling means on a vehicle determining the speed at which it may 95 run, a run-down device adapted to change in accordance with the distance traveled by the vehicle and assume an ultimate condition in a distance less than the length of a block, and means controlled by said run-down device for governing the operation of said speed controlling means. 100 39. In a train control system for railroads divided into blocks, a normally inactive run-down device adapted when set into operation 105 to change gradually to an ultimate condition in accordance with the distance traveled by the vehicle, said distance being less than the length of a block, train control means having its condition changed when the run-down device attains its ultimate condition, and traffic controlled means partly on the vehicle and partly along the track for automatically rendering said run-down device 110 active or inactive. 115 40. Automatic train control equipment for railway vehicles comprising a run-down device arranged to change gradually toward an ultimate condition in accordance with the distance traveled by the vehicle, speed control apparatus and control means therefor adapted to enforce predetermined speed limits for the vehicle, and means whereby said apparatus is governed by said run-down device when it attains its ultimate condition. 120 125 41. In an automatic speed control system for railroads divided into blocks, speed control apparatus on a vehicle adapted to enforce a normal maximum speed limit and effective when set into operation to enforce 130

- predetermined lower speed limits, a distance measuring device adapted to change to an ultimate condition in accordance with the movement of the vehicle, a controlling circuit for said apparatus governed by said device as the latter attains its ultimate condition, and means partly on the vehicle and partly along the track for governing said apparatus and said device in accordance with traffic conditions ahead. 46. In an automatic train control system for railroads having tracks divided into blocks, automatic train control apparatus on a vehicle of the type which once set into operation continues in operation until restored, automatic means partly on the track and partly on the vehicle for restoring said apparatus during the progress of the vehicle through a block provided the next block in advance is not occupied, said means being ineffective in an occupied block although the next block in advance thereof may not be occupied. 70
- 10 42. In an automatic speed control system for railroads divided into blocks, normally inactive speed control apparatus on a vehicle, a normally inactive run-down device on the vehicle governed in accordance with the movement thereof, traffic controlled means for rendering said apparatus and run-down device active, a normally closed circuit controller opened by said run-down device after the vehicle has traveled a predetermined distance, and a controlling circuit for said apparatus including said circuit controller. 47. In an automatic train control system for railroads having tracks divided into blocks, automatic train control apparatus on a vehicle including normally energized devices having a tendency to assure the active condition, said apparatus when set into operation continuing in operation until restored, control means on the vehicle adapted to be influenced from the trackway for setting said apparatus into operation, a plurality of trackway devices in each block controlled in accordance with traffic conditions in the next block in advance and each effective to influence said control means on a passing vehicle to set said apparatus into operation, and automatic traffic controlled means for restoring said apparatus. 80
- 15 43. In an automatic speed control system for railroads divided into blocks, speed control apparatus on a vehicle, a run-down device adapted to change to an ultimate condition, a circuit controller actuated by said device when it attains its ultimate condition, and means governed by said circuit controller for influencing the condition of said apparatus. 48. In an automatic train control system for railroads having tracks divided into blocks, automatic train control apparatus on a vehicle adapted when set into operation to continue in operation until restored, and automatic means partly on the vehicle and partly on the track and including a plurality of track devices in each block for setting said apparatus into operation or restoring it to its initial condition dependent upon the presence or absence of another train in the next block in advance, said means being ineffective to restore said apparatus in an occupied block although the next block in advance thereof may not be occupied. 90
- 20 44. In an automatic train control system for railroads having tracks divided into blocks, automatic train control apparatus on a vehicle adapted when set into operation to continue in operation until restored, control means on the vehicle adapted to be influenced from the trackway, trackway means associated with each block and governed in accordance with traffic conditions in the next block in advance for cooperating with said control means on the vehicle and cause restoration of said apparatus when said next block in advance is unoccupied, and means acting after the vehicle has traveled through a given block with its train control apparatus in operation for preventing such restoration by the trackway means associated 100
- 25 45. In an automatic train control system for railroads having tracks divided into blocks, automatic train control apparatus on a vehicle adapted when set into operation to impose a continuing restriction on the movement of the vehicle until restored, automatic restoring means partly on the vehicle and partly on the track for restoring said apparatus during the progress of the vehicle through the first part of a block when the next block in advance thereof is not occupied, and means capable of restoring said apparatus while said automatic restoring means is ineffective. 49. In an automatic train control system for railroads having tracks divided into blocks each provided with a normally closed track circuit, the length of said blocks affording braking distance for the normal running speed of trains therein, the combination with automatic brake control apparatus on a vehicle acting whenever once set into operation to impose a continuing restriction upon the movement of the vehicle until said apparatus is restored, of cooperating trackway means and car-carried means for controlling the initiation and restoration of said apparatus, said trackway means being associated with each block and responsive to the occupancy of the next block in advance, said cooperating means acting automatically to initiate operation of said apparatus on a vehicle in a block if the next block in advance is then occupied, and to re- 105
- 30 110
- 35 115
- 40 120
- 45 125
- 50 130

store said apparatus automatically in any block only if the remaining portion of that same block in advance of the vehicle and also all of the next block in advance are unoccupied.

50. In a system of automatic train speed control for railroads having tracks divided into blocks each provided with a normally closed track circuit, said system acting automatically to enforce predetermined restrictions upon the speed of a vehicle during its progress dependent upon the presence or absence of other vehicles immediately ahead, the combination of automatic brake control apparatus on a vehicle including speed responsive means determining the actual speed of the vehicle, cooperating trackway and car-carried means for governing the operating condition of said apparatus and determine the speed restriction to be

effective, said trackway means being associated with each block and having its controlling condition dependent upon the presence or absence of cars in the next block in advance, said trackway and car-carried cooperating means acting automatically to render said apparatus on a vehicle effective in a block whenever the next block in advance is occupied and thereby establish predetermined restrictions upon the speed of the vehicle corresponding to its position in said block, said cooperating means also acting automatically to control said apparatus and relieve such speed restrictions while the vehicle is in any block only if at least the remaining portion of that block ahead of the vehicle and all of the next block in advance are unoccupied.

CHARLES S. BUSHNELL.
